UNITED STATES PATENT OFFICE.

FRANK P. COLLIER, OF WILMETTE, ILLINOIS.

BRAKE-SHOE.

No. 806,239.

Specification of Letters Patent.

Patented Dec. 5, 1905.

Application filed March 13, 1905. Serial No. 249,782.

To all whom it may concern:

Be it known that I, FRANK P. COLLIER, a citizen of the United States, residing at Wilmette, in the county of Cook and State of Illinois, have invented new and useful Improvements in Brake-Shoes, of which the following is a specification.

The object of this invention is to reinforce and strengthen a brake-shoe in a simple and inexpensive manner, to avoid fracture in handling and in service, and to prolong the life of the shoe.

I have shown one embodiment of the invention in the accompanying drawings, in which—

Figure 1 is a perspective view of the plate. Fig. 2 is a longitudinal sectional view. Fig. 3 is a top plan view. Fig. 4 is a transverse sectional view on the line 4 4 of Fig. 3.

Referring to the drawings, 5 designates the plate, which is imperforate and curved to conform to the usual curvature of the back of the shoe. The edges 6 of the plate are beveled to make a locking engagement with the body 7. The body is cast on the plate, and the latter is cut out at 8 on its side edges to permit the body metal to flow up and form the attaching-lug 9. The end lugs 10 and the guide-lugs 11 are also formed by the body metal which flows up around the sides and ends of the plate. The plate is located beneath the attaching-lug and the end and guide lugs and is exposed on the back of the body of the shoe between said lugs.

I have shown the invention embodied in a

solid cast-iron shoe of a common type; but it will be understood that it can be used as well 35 in connection with composite shoes and in shoes of the many different types common in the art.

The plate reinforces and strengthens the shoe against fracture in handling and in service, and it can be embodied in a shoe at very little additional cost. It enables the shoe to remain in service until the body or wearing part has practically been worn away entirely, and thereby greatly prolongs the life of the 45 shoe and secures the maximum degree of service therefrom.

Without limiting myself to the exact construction and arrangement of parts herein shown and described, what I claim, and desire 50 to secure by Letters Patent, is—

A brake-shoe comprising an imperforate back plate bent to conform to the curvature of the shoe and having uniform curvilinear surfaces, and a body cast on said plate and having at each end integral end and guide lugs, said plate being of less length and width than the body and located beneath said lugs and exposed therebetween and having its edges beveled to make locking engagement with the 60 body.

FRANK P. COLLIER.
